PORTABLE BINDING MACHINE AND
PEGBOARDCharles Edward Emmer, Chicago, Ill., assignor to
General Binding Corporation, Chicago, Ill., a
corporation of Illinois

Application March 10, 1947, Serial No. 733,578

8 Claims. (Cl. 11—1)

1

My invention relates to small, compact portable binding machines for binding perforated sheets with a back member such as a flexible element of plastic material or the like by opening the fingers of the binding element to permit easy assembly of sheets thereon.

Specifically the invention deals with a binding machine and peg board that opens resilient curled fingers of a back member and is suitable for office use, being light in weight, easily stored, and conveniently operated by hand on a desk or table.

It is a further object of the invention to provide a lightweight compact portable binding machine adapted to be operated by unskilled workers and arranged to receive and open the curled fingers of a binding element so that perforated sheets can be easily threaded on the fingers.

A further object of the invention is to provide a binding machine for binding elements having flexible curled fingers that are quickly opened by the machine without twisting or distorting the back member or the resilient fingers.

Another object of the invention is to provide a binding machine for use with binding elements having a backbone and curled sheet-receiving fingers opened by the machine to form hooks for perforated sheets resting on a platform of the machine whereby the sheets can be easily arranged for using the machine as a peg board.

Another object of the invention is to provide a portable hand-operated binding machine for binding books with binding elements having flexible curled fingers and which is useful with a variety of back sizes and shapes.

A still further object of the invention is to provide a hand-operated portable book binding machine with a trigger-release mechanism to increase the speed of the binding operation.

Another specific object of the invention is to provide a book binding machine for use with binding elements having curled resilient fingers wherein the binding elements are merely dropped into position in the machine and are held against distortion in recesses of the machine.

The novel features which I believe to be characteristic of my invention are set forth in particularity in the appended claims. My invention, itself, however, both as to its organization and method of operation, together with further objects and advantages thereof, may best be understood by reference to the following description taken in connection with the accompanying drawings.

As shown in the drawings:

2

Figure 1 is a top plan view of one embodiment of my invention and showing a binding element of the curled finger type therein;

Figure 2 is a fragmentary top plan view of the machine of Figure 1 but showing the machine in open position for holding the fingers of the binding element in uncircled position for receiving perforated sheets or the like.

Figure 3 is a bottom plan view of the machine of Fig. 1;

Figure 4 is a side view of the left hand side or end of the machine shown in Figure 1;

Figure 5 is a transverse cross sectional view taken along the line V—V of Figure 4;

Figure 6 is a longitudinal cross-sectional view taken along the line VI—VI of Figure 3;

Figure 7 is a top plan view showing how the machine of Figure 1 may be used as a peg board;

Figures 8 and 9 are side and fragmentary top views, respectively, showing a modification of my invention incorporating a quick release mechanism;

Figure 10 is a fragmentary cross sectional view through the axis X—X of Figure 2 illustrating how the spreader elements engage the fingers of the binding element and

Figures 11 and 12 are cross sectional views through axis XI—XI of Figure 1 and XII—XII of Figure 2, respectively.

As shown on the drawings:

As will be evident from examination of Figures 1 to 4 the machine of my invention may be divided into three components, the frame structure 21, the binding element opening mechanism 25, and the operating mechanism 36. The frame serves as a support upon which the various operative elements are mounted and also provides a sustaining surface for the sheets of paper or the like bound by the binding element,

the binding element opening mechanism serves to grip and support the binding element opening, and the operating mechanism serves to actuate the binding element opening mechanism. A binding element 22 is shown mounted in the machine and has a backbone portion 21 from which curled fingers 23 project at spaced intervals.

The binding element opening mechanism 25 includes a shiftable backboard or support member 20 upon which binding element 22 is placed for opening. This support includes a plurality of forwardly extending teeth 24 each of which has an upwardly extending tip portion 26, which may be seen in side view in Figure 4. Backing plate 28 is attached to support member 20 immediately

below that member and is provided with a plurality of depressed portions 30 to coact with non-depressed adjacent portions in forming grooves for receiving and supporting the fingers of the binding element 22. The shape of these depressed portions 30 will be evident from examination of Figures 4 and 10.

A spreader mechanism 32 is provided to engage the curled fingers of the binding element to open the fingers from the position shown in Figure 1 to that of Figure 2. This spreader may, for example, include a plate of transparent plastic material or other suitable material as shown and is provided with a plurality of extending hook elements 34 to engage the fingers 23 of binding element 22, each hook having a forwardly extending portion 33 which extends in the spaces between the fingers within the binding element 22 when the spreader 32 is positioned as in Figure 1 and a sidewardly extending portion 31 also fitting in these same spaces between the fingers but arranged to engage the fingers 23 of binding element 22 when the machine is shifted to the position of Figure 2.

The operation of the machine in opening the binding element 22 from the position of Figure 1 to that of Figure 2 may best be understood by reference to Figures 1, 2, 11, and 12, the latter two figures consisting of cross-sectional views through the indicated cross sections of Figures 1 and 2. In the positions of Figures 1 and 11, the back-board or support member 20 and the spreader 32 are positioned relative to each other so that the hook elements 34 extend within binding element 22 but are in interleaved relation with the fingers 23 thereof. That is, the elements 34 of spreader 32 are aligned with the upwardly extending portions 26 of support 20 so that the hook portions 31 do not engage the fingers 23 and the binding element 22 may be positioned by simply laying it across the mechanism as shown in Figure 1. In this position the backbone 21 of the binding element 22 is in engaging relationship with the upwardly extending portions 26 of support 20, although no pressure is exerted therebetween other than that associated with the tendency of binding element 22 to roll off the mechanism. The binding element 22 with the backbone 21 thereof hooked over the portions 26 is supported on backing plate 28, this plate being in engagement with the curled fingers 23.

As will be described in further detail hereafter, the spreader 32 and the backboard 20 are moved relative to each other so as to move hooks 34 parallel to the backbone 21 and then to retract these hooks transversely to the direction of the backbone 21 until the position shown in Figure 2 is finally reached. This motion is accomplished by first sliding support 20 and backing plate 28 in the direction of the backbone 21 so as to cause portions 31 of the hooks 34 to extend within fingers 23 and then retracting spreader 32 so as to engage the fingers 23 and open them to the position of Figure 2. In the condition of Figure 2, the elements 34 engage the corresponding fingers 23 of binding element 22, and pull these fingers to uncurl them as shown in Figure 12. The backbone 21 of binding element 22 is held by the upwardly extending portions 26 of support member 20 so as to anchor the binding element. As will be evident from Figure 12, in this condition the binding element is open so as to leave only an upwardly projecting end portion of each finger 23, and perforated material such as paper or the like may be inserted by

threading it on these projecting ends of the fingers.

Figure 10 shows clearly how the portions 31 of hook elements 34 of spreader 32 engage the separate fingers 23 of binding element 22 so as to pull these fingers in direction away from support 20 and backing plate 28 and unwind the fingers. This view further shows how the fingers 23 of binding element 22 rest in depressed portions 30 of backing plate 28, which portions are disposed so as to engage the separate fingers 23.

It is the purpose of the operating mechanism shown generally at 36 to move the spreader 32 from non-engaging condition shown in Figure 1 to the finger opening or engaging position shown in Figure 2. To this end, mechanism 36 includes an operating handle 38 attached to shaft 40 so that rotation of the handle causes corresponding rotation of the shaft. As will be evident from examination of Figures 3, 5 and 6, a pair of cam cranks 42 are mounted upon shaft 40. A pair of crank rods 44 extend from cam cranks 42 to the downwardly extending portions 46 of spreader 32. These portions are anchored to spreader 32 so that as shaft 40 is rotated in the clockwise direction as seen in Figure 6, spreader 32 is retracted to a spaced position relative to support 20. The downwardly extending portions 46 of spreader 32 are connected by rod 48, Figure 3, which is biased by spring 50 to urge spreader 32 to the non-engaging position shown in Figures 1 and 3, so that the spreader 32 and support 20 are naturally positioned in the binder element receiving condition of Figure 1. In addition to shifting spreader 32 to a spaced position relative to support 20, the cams 42 operate to slide support 20 relative to spreader 32 in the direction of the backbone of binding element 22. This is accomplished by the cam portions 52 of the cam cranks 42. As will be evident from Figure 5, these portions of the cam cranks 42 are bent in the direction of the backbone of the binding element 22, Figure 1, and ride against rotatable followers 54. The followers 54 are attached to support member 20 by pivots 56 so that rotation of shaft 40 associated with operation of handle 38 causes support 20 and backing plate 28, together with binding element 22 thereon, to shift relative to spreader 32 and the remainder of the unit. Positive operation of the cam portion of cam cranks 42 is achieved by arranging the cranks so that they engage opposite sides of the followers 54, thus causing one cam 42 to oppose motion of support member 20 in one direction and the other to oppose motion of support 20 in the opposite direction. This structure will be evident from Figure 5.

It is thus evident that support 20 and backing plate 28 assume a position in the direction of the axis of the backbone of binding element 22 determined by the position of the operating handle 38 on shaft 40 and spreader 32 assumes a position in direction transverse to the direction of the backbone of binding element 22 also determined by the position of handle 38. Inasmuch as cam elements 52 are shaped so as to cause support member 20 to complete its shifting operation before appreciable motion of spreader 32 takes place, the binding element 22 is shifted from the non-engaging position shown in Figure 1 to a position where portions 31 of hook elements 34 are capable of engaging fingers 23 before appreciable movement of spreader 32 in the retracting or binding element opening direction takes place. Spreader 32 is thereby positioned relative to binding element 22 so as to engage

the extending fingers 23 of binding element 22, thus causing the binding element to assume the open position of Figure 2 upon further rotation of handle 38 and the consequent retraction of spreader 32.

It will be observed that rotation of handle 38 acts to move support 20 and backing plate 28 as a unit since these two elements are attached to each other by screws 56, Figures 11 and 12. Since the binding element 22 is supported in its entirety by these elements, this motion of support 20 and backing plate 28 has no tendency to distort the backbone of binding element 22 or twist the fingers 23 but on the contrary provides a complete supporting assembly which is shifted as a unit. Thus the only effect of the machine on the binding element is to unwind the fingers to the extent necessary to open them to a condition to receive a perforated medium such as paper.

The function of latch 58, Figure 4, is to hold spreader 32 against the action of spring 50 when in the position shown in Figure 2. To this end, latch 58 is mounted on pivot 60 of handle 38 so as to engage pin 62 when pulled to the position shown in Figure 2. Latch 58 is biased to the pin engaging and pressure sustaining position by spring 64 which urges operating knob 66 to a spaced relationship with cleat 68 which is mounted on handle 38, thereby urging rod 70 in the direction of the axis of handle 38 and tending to rotate latch 58 in the clockwise direction about pivot 60. Thus, as the handle 38 is rotated to the position shown in Figure 2 where the fingers 21 of binding element 22 are unwound, the latch 58 engages pin 62 and the handle may be released without causing spring 50 to return the mechanism to the position shown in Figure 1.

In order to accommodate binding elements of different diameters and sizes, pin 62 is provided with a square head portion which may be inserted into any one of a plurality of correspondingly shaped openings 72 in curved detent or support member 74. Selection of an appropriate opening 72 permits choice of the separation of spreader 32 and support 20 when latch 58 engages, thus permitting adjustment of the machine in accord with the size of the binding element to be opened.

Figure 7 shows one method of utilizing my improved binding machine as a peg board. The binding element 22 is mounted on the unit in the normal fashion and handle 38 is rotated to open or unwind the fingers 23 so as to permit removal and insertion of sheets of paper or other medium. In this condition, the fingers 23 extend upwardly from the upper surface plate 76 of the binder. It is thus possible to mount a plurality of perforated sheets 78, 78a, 78b, etc., in aligned side by side relation, partially overlapped if desired, by threading the upstanding finger portions selectively through the perforations. A T-square or similar device 80 may then be used to locate a particular line across all the sheets to enable the operator to study the entries on this common line of the several sheets and to alter these entries as desired. In this fashion the portable binding machine not only operates as a device to permit convenient binding of sheets 78, 78a, 78b, etc., in the binding element 22 but also enables convenient utilization and change of the information contained on a plurality of sheets.

Figures 8 and 9 show an alternative embodiment of my invention having means quickly to release the handle 38 to allow the binding ele-

ment 22 to pass from the open condition shown in Figure 2 to the closed position of Figure 1, thereby binding the sheets contained therein. In this modification of my invention the latch 58 is provided with an extension 82 which projects beyond the pin 62. A disengaging lever 84 is pivotally mounted on pin 86 carried by the side wall of the frame 21 and is biased against a pin 88 by spring 90. Lever 84 is constructed of such length that when the operating handle portion 92 is depressed to the position shown in the dotted lines of Figure 8, the extension 82 of latch 58 is engaged by the extending end of lever 84, thereby disengaging latch 58 from pin 62 and causing spring 50 (Figure 3) to return the mechanism to the position shown in Figure 1.

The disengaging lever 84 appreciably increases the speed within which an operator can assemble various sheets to form a complete bound volume for the reason that the operating handle portion 92 is disposed relatively far down on the upper surface plate 76 so as to be in a position close to the position naturally assumed by the hands of the operator when inserting pages in the binding element. The operator can accordingly depress operating portions 92 with a simple hand motion and cause the binding element to assume the curled or assembled position.

The above descriptions will make it clear that the portable binding machine of this invention is easily operated by unskilled workers who merely drop the binding element into the machine so that the binding element fingers lie in the grooves of the support mechanism 20 while the back bone 26 of the binding element is engaged by the teeth 26 between the grooves. The handle 28 is then pulled to rotate shaft 40 for shifting the support mechanism to carry the fully supported binding element fingers in the path of the hooks which, upon further pulling of the handle, are retracted away from the back bone to open the fingers. The perforated sheets are then threaded on the open fingers which, even in their opened positions, have upstanding hook-like free ends to retain the sheets. The handle is then released, the fingers curl back under their own power to their closed positions, and the bound book is lifted from the machine.

As will be evident from the drawings, the machine can accommodate binding elements of different lengths and diameters. Thus binding elements having fingers of different length can be accommodated by the machine since these fingers are opened to any predetermined uncircled position by the variable setting for the retaining pin 62. If desired, two or more independent binding operations can be simultaneously carried out on the machine by merely placing the combs in end to end relation on the machine.

While I have shown particular embodiments of my invention, it will of course be understood that I do not wish to be limited thereto since many modifications both in the elements employed in their cooperative structure may be made without departing from the spirit and scope of my invention. I, of course, contemplate by the appended claims to cover any such modifications as fall within the true spirit and scope of my invention.

70 I claim as my invention:

1. A portable binding machine for a book binding element having a backbone and resilient curled fingers comprising a frame, a backboard mounted on said frame and shiftable along an axis thereon, said backboard having surfaces to

support said fingers and having elements to hold said backbone along an axis parallel to said first axis, a spreader shiftably mounted on said frame for motion in direction perpendicular to said first axis, said spreader having a plurality of hooks with ends extending in common direction to engage said fingers, a resilient device to urge said backboard and said spreader to relative positions wherein said hooks extend within said binding element and are in interleaved relation with the fingers thereof, and an operating member to overcome said device including a rockable member having operable engagement with said backboard, to shift said backboard along said frame in the direction of a longitudinal axis of the binding element to position said fingers for engagement with said hooks and a link pivotally connected between said rockable member and spreader to shift said spreader transversely of the longitudinal axis of the binding element to open or unwind the fingers thereof.

2. A portable binding machine for a book binding element having a backbone and resilient curled fingers comprising a frame, a backboard mounted on said frame and shiftable along an axis thereon, said board being shaped to support said fingers and having upwardly extending portions to hold said backbone along an axis parallel to said first axis, a spreader shiftably mounted on said frame for motion along an axis perpendicular to said first axis, said spreader having a plurality of hooks with ends extending in a common direction to engage said fingers, an operating shaft rotatably mounted in said frame, a cam mounted on said shaft to rotate therewith, a crank connected to said cam and said spreader so that said spreader is shifted along said last axis as said shaft is rotated, said cam having a cam surface disposed to engage said backboard and extending in the direction of said first axis, said surface and said crank being positioned so that rotation of said shaft causes said backboard to shift in amount to permit the ends of said hooks to engage said fingers and said spreader to shift to open said fingers, and a spring disposed to urge said spreader and said backboard to positions relative to each other wherein said hooks extend within said binding element but in interleaved relation with the fingers thereof, whereby a binding element may be placed on said binder without engaging said hooks and said shaft may be rotated to open said binding element to a condition to receive perforated sheets of medium.

3. A portable binding machine for a book binding element having a backbone and resilient curled fingers comprising a frame, a backboard mounted to shift along an axis on said frame and shaped to engage said backbone, a spreader mounted on said frame so as to shift in direction perpendicular to the direction of shifting said backboard, said spreader having a plurality of hooks with ends extending in a common direction to engage said fingers, said hooks being located along a common axis parallel to said backbone of said binding element, rockable means operatively connected with said backboard and said spreader and operable to shift said backboard in the direction of a longitudinal axis of said binding element so as to cause said hooks to engage said fingers and to shift said spreader in a direction transversely of the longitudinal axis of the binding element so as to open said fingers to a position to receive perforated sheets of medium and adjustable means to retain said last means

in one of several predetermined positions and accommodate said spreader for various diameters of binding elements and to hold said fingers in an open position.

5. 4. A portable binding machine for a book binding element having a backbone and resilient curled fingers comprising a frame, a backboard mounted on said frame and shiftable along an axis thereon, said backboard having surfaces to support said fingers and upwardly extending teeth to hold said backbone along an axis parallel to said first axis, a spreader shiftably mounted on said frame for motion along an axis perpendicular to said first axis, said spreader having a plurality of hooks with ends extending in a common direction to engage said fingers, an operating shaft rotatably mounted in said frame, a cam mounted on said shaft to rotate therewith, a crank connected to said cam and said spreader so that said spreader is shifted along said last axis as said shaft is rotated, said cam having a cam surface disposed to engage said backboard and extending in the direction of said first axis, said cam surface and said crank being positioned so that rotation of said shaft causes said backboard to shift in amount to position said hooks to alignment with said fingers and to shift said spreader to open said fingers, a spring disposed to urge said spreader and said backboard to positions relative to each other wherein said hooks extend within said fingers and are in interleaved relation therewith, whereby a resilient binding element may be placed on said binder without engaging said hooks and said shaft may be rotated to open or unwind said fingers to receive perforated sheets of a medium, and means to retain said spreader in the finger opening condition, said means comprising a latch mounted to rotate with said shaft and a retaining member in cooperative relationship with said latch so that said latch swings into engaging relation therewith upon predetermined rotation, and a release bar supported by said frame to disengage said latch and permit said spring to return said spreader and said backboard to said positions.
- 20 5. In a portable binding machine for use with resilient binding elements provided with a backbone portion and curled finger portions, a frame, a shiftable backboard on said frame for carrying a binding element, a spreader adapted for reciprocation on said frame relative to said backboard for engaging said finger portions of said binding element and an actuating mechanism carried by said frame comprising an operating element, a rotatable shaft controlled thereby, a cam on said shaft, a cam follower carried by said backboard and engageable with said cam and a link connected with said spreader and said cam whereby actuation of said operating element will rotate said shaft and move said cam to produce shifting of said backboard and reciprocation of said spreader.
- 30 6. In a portable binding machine for use with resilient binding elements provided with a backbone portion and curled finger portions, a frame, a shiftable backboard on said frame for carrying a binding element, a spreader adapted for reciprocation on said frame relative to said backboard for engaging said finger portions of said binding element and an actuating mechanism carried by said frame comprising an operating element, a rotatable shaft controlled thereby, a cam on said shaft, a cam follower carried by said backboard and engageable with said cam and a link connected with said spreader and said cam

whereby actuation of said operating element will rotate said shaft and move said cam to produce shifting of said backboard and reciprocation of said spreader, said actuating mechanism further including a manually controlled latch on said operating element, a detent on said frame cooperable with said latch and a trigger-release lever pivotally mounted on said frame engageable with said latch whereby said actuating mechanism may be selectively locked in a predetermined position and quickly released by actuation of said trigger-release lever.

7. A binding machine for use with a binding element having a backbone and resilient curled fingers, comprising: a frame, a backboard mounted on said frame for reciprocal movement in a rectilinear path between first and second positions, means defining spaced upright elements on said backboard aligned in the direction of movement thereof and arranged to extend between fingers of a binding element and engage the backbone thereof, support means projecting from said backboard and having first surface portions aligned with the spaces between said upright elements for receiving the fingers of a binding element thereagainst and having means defining second surface portions at either side of and normal to said first surface portions for engaging the sides of the fingers of a binding element positioned on said backboard, a spreader having a plurality of hooks extending toward said backboard in spaced relation to said first surface portions and aligned with said upright elements in said first position of said backboard, said backboard being movable from said first position to said second position to align the fingers of a positioned binding element with said hooks, and said spreader being rectilinearly movable on said frame generally parallel to said first surface portions and away from said spaced upright elements for engaging said hooks with the fingers of a positioned binding element and uncurling the fingers.

8. A portable binding machine for a book binding element having a backbone and resilient

curled fingers, comprising: a frame, a backboard mounted to shift along an axis on said frame and having elements to engage the backbone of said binding element, a spreader mounted on said frame so as to shift in direction perpendicular to the direction of shifting of said backboard, said spreader having a plurality of hooks with ends extending in a common direction to engage said fingers, said hooks being located along a common axis parallel to the backbone of said binding element, rockable means operatively connected with said backboard and said spreader and operable to shift said backboard in the direction of the longitudinal axis of the binding element so as to position the binding element fingers in engaging relation with said hooks and to shift said spreader in a direction transverse to the longitudinal axis of the binding element so as to open or unwind the fingers thereof, and adjustable means to retain said rockable means in one of several predetermined positions and accommodate said spreader for various diameters of binding elements and to hold the fingers of the binding element in the open or unwound condition, and means to disengage said retaining means so as to quickly release the fingers to rebind said medium.
